D. B. PEEBLES.

GAS-GOVERNOR.

No. 172,163.

Patented Jan. 11, 1876.

Fig. 1

UNITED STATES PATENT OFFICE.

DAVID B. PEEBLES, OF EDINBURGH, SCOTLAND.

IMPROVEMENT IN GAS-GOVERNORS.

Specification forming part of Letters Patent No. 172,163, dated January 11, 1876; application filed October 8, 1875.

To all whom it may concern:

Be it known that I, DAVID BRUCE PEEBLES, of Edinburgh, Scotland, have invented a new and Improved Gas-Governor, of which the following is a specification:

This invention relates to improvements in governors used for regulating the pressure of gas, which improvements are designed to adapt it for regulating the volume of the gas, more particularly to those used for single jets, such as in public lamps.

Between two half cases or shells, made of glass, cast-iron, or other suitable metal, but by preference of cast-iron, a flexible diaphragm, of leather or other similar material, is fixed, and a passage for the gas is made between the upper and lower chamber through the projecting part of the case. In the lower half a recess is made to receive a disk of sheet-tin or other suitable metal not acted on by gas. In the center of this disk a hole is made, into which the conical point of a regulating-screw is placed, so that by moving it the hole can be opened or closed. The top of the screw is surrounded by a bead or feather, forming a recess, into which wax or fusible metal can be run to receive a stamp for a seal.

The valve, made of block-tin or a suitable fusible alloy, is of a double conical shape, with a stem at one end. The other end rests in a step made in the head of the center screw, which keeps the metal disks to the diaphragm.

The bottom of the burner-tube acts as a valve-seat, and by this arrangement the valve can be taken out for cleaning by unscrewing the burner-tube, without taking the governor to pieces.

Figure 1 is a sectional elevation of the governor; and Fig. 2 is a plan of the lower portion, the upper and lower portions being separated on the line *x x*.

Similar letters of reference indicate corresponding parts.

A is the lower part, and *B* the upper part, which are bolted together on the line *x x*, with a flexible diaphragm, *C*, between them, to be used for raising and lowering the valves. The gas enters below the diaphragm through pipe *E*, and the passage *F* to the upper side of the diaphragm is located in the lateral extension *G* of the case. The object of this is to admit of using the regulating-screw *H*, in

combination with the perforated disk *F*, so that the volume of gas may be varied at will. From the extension *G* the gas passes through *I* into the upper part of the governor, from which it escapes by the valve *D*, which, like its corresponding valve in the wet governor, rises up and lessens the flow to the burner, when, by reason of greater pressure below the diaphragm, a greater volume passes through passage *F*, the diaphragm being raised whenever the pressure increases, and when the pressure falls, so that a lesser volume passes at *F*, the diaphragm falls, and affords a freer exit at the valve *D*. This valve *D* is set detachably in a little step, *J*, on the top of the diaphragm, and it is kept in position by its stem extending up into the exit-tube, so that by taking off the tube *K*, and inverting the governor, the valve can be taken out at any time to remove the matters collecting on it, or for any desired purpose, without having to open the governor. *L* is the bead or flange surrounding the top of the screw, for holding a wax or other seal.

The inlet-pressure of the gas, acting on the lower surface of the diaphragm, tends to raise it and close the valve; but, as it gets through the regulating-hole, pressure is established on the upper as well as the lower surface of the diaphragm, and the equilibrium is only disturbed by the weight of the diaphragm and valve, which, being constant, establishes, in conjunction with the regulating-hole, an unvarying volumetric discharge of gas. The apparatus is therefore a volume-regulator—not a pressure-regulator.

Having thus described my invention, I claim as new and desire to secure by Letters Patent—

1. The gas-passage *F*, located in an extension, *G*, outside of the flexible diaphragm, and provided with a regulating-plug, substantially as specified.
2. The valve *D*, detachably supported on and in combination with the diaphragm, and having its stem extended into the exit-tube, substantially as specified.
3. The combination of the bead or flange *L* with the adjusting-screw, to contain a seal, substantially as specified.

D. BRUCE PEEBLES.
